UNITED STATES PATENT OFFICE.

JOSEPH A. GASSE, OF CLAREMONT, NEW HAMPSHIRE.

SIGNAL-CONTROLLING MEANS FOR RAILWAY-GATES.

1,128,439.

Specification of Letters Patent. Patented Feb. 16, 1915.

Original application filed September 12, 1911, Serial No. 648,939. Divided and this application filed November 11, 1913. Serial No. 800,290.

To all whom it may concern:

Be it known that I, JOSEPH A. GASSE, subject of George V, King of Great Britain and Ireland, residing at Claremont, in the county of Sullivan and State of New Hampshire, have invented certain new and useful Improvements in Signal-Controlling Means for Railway-Gates, of which the following is a specification.

My invention relates to railway equipment and particularly to signal mechanism adapted to be attached to the arm of a railway gate to indicate by a visual and audible signal when the gate is lowered and raised and forms a division of my pending application, Serial Number 648,939, filed September 12, 1911, for gate controlling mechanism for railroads.

A further object of the invention is to provide a signaling device adapted to be attached to the arm of a crossing gate when, when the gate is lowered, will cause the lighting up of a signal lamp and cause the actuation of an electric bell and which will be automatically thrown out of operation when the gate rises to an open position.

A further object of the invention is the provision of a very simple controlling mechanism for signals adapted to be actuated by gravity as the member upon which the signals are mounted moves from a vertical to a horizontal position.

Other objects will appear in the course of the following description.

In the accompanying drawings: Figure 1 is a view of a railway gate in its closed position with my signaling mechanism applied thereto. Fig. 2 is a fragmentary side elevation of a portion of the gate in a half raised position. Fig. 3 is a perspective detail view of the gravity actuated controlling member. Fig. 4 is an enlarged vertical section showing a portion of the arm of the controlling member and the roller thereon.

Referring to these drawings A designates a rail of a track and B the casing inclosing the gate arm actuating mechanism. The gate arm C is of any ordinary or usual construction and is rotatably mounted at c preferably upon a shaft projecting out from the casing B. This gate arm is counterweighted as is usual and normally is in a raised position but upon the approach of a train this gate arm is lowered either by automatic means or by hand operated means

into a position across the roadway intersected by the line of track. It will be understood, of course, that there may be a plurality of these gate arms controlling a grade crossing but I have only shown one of these 60 arms inasmuch as all of the arms will be similarly equipped.

Mounted upon the gate arm is an electric signal bell 2 of any usual or ordinary construction and also mounted upon the gate arm and adjacent the signal bell is an electric light 3. Electrically connected to the signal bell and to the signal light is a battery 4, the conductor connecting the battery with the bell and light being designated 5. Pivotedly mounted upon the gate so as to swing in a vertical plane as the gate descends is an arm 6 the lower end of which is counterweighted as at 7. The arm is pivoted at 8 and the upper end of the arm, 75 as illustrated clearly in Figs. 3 and 4, is provided with a roller designated generally 9. The body of this roller is formed of non-conducting material designated 10 and surrounding this body 10 is a shell 11 of 80 metal. This shell is interrupted; that is, the shell does not extend entirely around the roller but a portion 12 of the body 10 is left uncovered. The inner end of the shell extends inward as at 13 and contacts 85 with any suitable brush 14 whereby the current may be conducted from the shell 11 to a wire 5^a which extends to the pivotal center 8 of the arm 6. It is to be understood, however, that if the arm 6 is of metal, the 90 wire 5^a may be omitted and the arm 6 used as a conductor. This wire 5^a is a return wire and extends to battery 4.

The roller 9 rotates against a plate 15 which is of non-conducting material and 95 which is fastened to the arm C in any suitably manner, and embedded or otherwise attached to this plate are the metal contact strips 16 and 17. These contact strips 16 and 17 are arcuate so that they are disposed 100 entirely in the path of travel of the roller 9 and so as to be contacted with by said roller. The contact strip 16 is connected by means of a wire 18 to one of the binding screws of the bell 2 and the strip 17 is connected by means of a wire 19 to one of the terminals of the electric light 3. It will be noted that the strips 16 and 17 are of different lengths, the strip 17 being longer than the strip 16. 110

It will be obvious that when the non-conducting portion of the roller 9 is in contact with the contact strip 16 no current will pass from the battery through the signal but that when the shell 11 is brought in contact with the strip 16 a circuit will be established through the battery 4, through the lamp 3, and through the bell signal 2. When the parts are in their vertical position 10 the roller 9 will be turned relative to the strip 16 with the non-conducting face 12 of the roller presented to both of the strips 16 and 17. As the gate descends however, the counterweight 7 will cause the upper 15 end of the arm to move over the contact strips 16 and 17 and as it moves the roller 9 will rotate until by the time the gate is partly lowered into the position shown in Fig. 2, the contact face or shell 11 of the 20 roller will contact with the strips 16 and 17 and thus the circuit through the signals will be completed, the bell will be sounded while the gate is being lowered and the light displayed.

25 It is desirable that the bell shall be sounded while the gate is being lowered but that the bell shall be silent after the gate is fully lowered, the light, however, continuing to burn. This is the reason for 30 making the contact strips 16 and 17 of different lengths. As the gate reaches a nearly lowered position the roller 9 moves off of the contact strip 16 but retains its contact with the strip 17 and as a consequence a 35 circuit remains completed through the wire 5^a, the battery 4, the wire 19, the light 3, the strip 17 and the shell 11. As the gate rises the bell will again ring until the gate is fully raised, by which time the roller 9 40 has rotated to such position as to break the engagement of the contact plate or shell 11 with the strips 16 and 17 and the circuit through the bell and light is broken.

The upper end of the roller 9 is formed 45 with a stop 20 which contacts with an arm 21 which extends outward from the upper end of the reduced portion 6^a of the arm 6, this reduced portion forming a pintle upon which the roller 9 rotates. By this means 50 the roller is stopped after it is rotated part-way around. This will insure a safe electrical connection between the roller and the strips obviate the necessity of having a roller so made as to exactly cover the arcuate strips 16 and 17 as it is rotated. In this latter case, if the roller wore out, or if the roller failed to roll properly, there would be trouble. By using the stop 20 and the arm 21, the roller may be cut to any size, 55 regardless of the length of the arcuate strips 16 and 17 and yet a proper electrical connection will be secured.

60 My invention it will be seen is extremely simple, may be easily applied to any gate now in use, and may be applied to various

forms of gate or may be applied to any other mechanism where it is desired to display a signal upon a movement of a member from a vertical to a horizontal position.

Having described my invention, what I claim is:

1. The combination with a pivoted member movable from a vertical to a horizontal position, of two signals thereon, a source of energy connected in open circuit with both 7 of said signals, gravity actuated means mounted upon the arm for closing a circuit through both of said signals as the arm moves from a vertical toward a horizontal position, and means for breaking the circuit 8 through one of said signals when the member nears its horizontal position.

2. The combination with a pivoted gate arm, of separate electrically actuated signals thereon, a source of energy connected 8 in open circuit with both of said signals, a pair of arcuate contact strips, each forming one terminal of the open circuit for each signal, one of said strips being longer than the other, and a contact member carried by 9 said arm and forming a common terminal of both circuits, and electrically connected with the battery, said arm being movable into electrical engagement with the contact strips as the gate moves from its vertical 9 to a horizontal position.

3. In a railway gate, the combination with a pivoted gate arm movable from a vertical to a horizontal position, of an electric signal thereon, a source of energy connected in open circuit with said electric signal, an arcuate contact strip mounted upon the gate arm and forming one terminal of said open circuit, a pivoted member mounted upon said gate arm and counterweighted to be retained in a vertical position, a roller mounted upon the pivoted member and having rolling engagement with the contact strip, and a contact member disposed upon the face of said roller and forming the other terminal of said circuit whereby as the gate arm descends the roller will be rotated in contact with the strip to bring the contact strip and the contact on the roller into electrical engagement to close 1 the circuit through the signal.

4. The combination with a pivoted gate arm, of an electrically mounted signal thereon, a source of energy connected in open circuit with said signal, an arcuate contact strip forming one terminal of said circuit, a counterweighted arm mounted upon the gate arm, a roller mounted upon the counterweighted arm and having rolling engagement with said contact strip, said roller being of non-conducting material, and a contact member embodying a shell partially surrounding the roller, said shell forming the other terminal of said circuit, whereby as the gate arm descends the roller 1

will be rotated by contact with the strip to bring the contact strip and the contact on the roller into electrical engagement to close the circuit through the signal.

5. 5. The combination with a pivoted member movable from a vertical to a horizontal position, of separate signals mounted upon the pivoted member, gravity actuated controlling means pivotally mounted upon the 10 said member, means actuated by the movement of the controlling means for displaying both of said signals as the arm moves from one extreme of its movement toward the other, and means for cutting off one of 15 said signals when the arm has reached the other extreme of its movement.

6. In a mechanism of the character described, the combination with a pivoted member movable from a vertical to a horizontal position, of a signal thereon, a source of energy connected in open circuit with 20 said signal, an arcuate contact strip forming one terminal of said circuit, a counter-

weighted pivoted arm mounted upon the member and normally held in a vertical position, a roller mounted upon the counter-weighted arm and having rolling engagement with the contact strip, a contact member disposed upon the face of said roller and forming the other terminal of said circuit whereby after the member moves from a vertical to a horizontal position the roller will be rotated in contact with the strip to bring the contact strip on the roller into electrical engagement to close the circuit 35 through the signal, and means for stopping the rotation of the roller after the contact member carried thereby has moved into engagement with the contact strip.

In testimony whereof I affix my signature 40 in presence of two witnesses.

JOSEPH A. GASSE. [L.S.]
